(57) **CLAIM**

The ornamental design for a lamp lens, as shown and described.

DESCRIPTION

FIG. 1 is a perspective view of front, top and right side of a lamp lens according to my new design;

FIG. 2 is a perspective view of rear, top and right side thereof;

FIG. 3 is a front view thereof;

FIG. 4 is a rear view thereof;

FIG. 5 is a right side view thereof;

FIG. 6 is a top view thereof;

FIG. 7 is a bottom view thereof;

FIG. 8 is a cross sectional view thereof taken along line 8-8 of FIG. 3; and,

FIG. 9 is a cross sectional view thereof taken along line 9-9 of FIG. 3.

The portions of the article in broken lines are shown for illustrative purposes only and form no part of the claimed design.

1 Claim, 8 Drawing Sheets
